Des. 229,558

Patented Dec. 11, 1973

229,558

SPIDER FOR A WHEEL

James L. Brainard, 6237 Kauffman Ave., Temple City, Calif. 91780, and Robert J. Palm, 18297 Midbury, Brea, Calif. 92621

Continuation-in-part of abandoned design application Ser. No. 191,579, Oct. 21, 1971. This application June 15, 1972, Ser. No. 262,948

Term of patent 14 years

Int. Cl. D12—16

U.S. Cl. D14—30 R

FIG. 1

FIG. 2

FIG. 3

FIG. 1 is a side elevation of a spider showing our new design;

FIG. 2 is a cross-section taken on line 2—2 of FIG. 1;

FIG. 3 is an elevation as seen from the opposite side of FIG. 1.

This application is a continuation-in-part of design application Ser. No. 191,579, filed Oct. 21, 1971, for a Wheel and now abandoned.

We claim:

The ornamental design for a spider for a wheel, as shown.
